UNITED STATES PATENT OFFICE.

EDGAR E. GREEVE, OF PITTSBURGH, PENNSYLVANIA, ASSIGNOR TO OIL WELL SUPPLY COMPANY, OF PITTSBURGH, PENNSYLVANIA, A CORPORATION OF PENNSYLVANIA.

CASING-ELEVATOR.

1,112,004.

Specification of Letters Patent. Patented Sept. 29, 1914.

Application filed January 23, 1913. Serial No. 743,727.

To all whom it may concern:

Be it known that I, EDGAR E. GREEVE, a citizen of the United States, residing at Pittsburgh, in the county of Allegheny and State of Pennsylvania, have invented certain new and useful Improvements in Casing-Elevators; and I do hereby declare the following to be a full, clear, and exact description of the invention, such as will enable others skilled in the art to which it appertains to make and use the same.

My invention relates to the construction of that class of devices commonly termed casing elevators used for raising and lowering, as well as connecting up, casing and tubing, in sinking oil, Artesian or gas wells.

It has for its several objects, the production of a casing elevator of a character which can be readily handled in the derrick and applied to the casing by a single operator, which can be opened and closed on the casing or tubing in close proximity to the derrick floor or the collar on the casing or tubing and without lowering the elevator below the collar more than is required to relieve the elevator of the weight of the casing.

It also has for its further object the provision of locking devices for the movable section of the elevator which will act automatically on the closing of the movable section, not only to secure the sections but also to secure the lock to prevent accidental release of the locking device when the weight of the casing or tubing is on the elevator.

To this end my invention generally stated embodies the combination in an elevator of a bail, a bail member on which the bail is journaled, a movable member pivoted on the bail member, and a locking mechanism whose release is controlled by the bail whereby the securing of the elevator in position on the casing or tubing is automatic, and the release of the locking mechanism is dependent on the withdrawal of the weight of the casing or tubing from the elevator.

In the drawings chosen for the purpose of illustrating my invention, the scope whereof is pointed out in the claims, Figure 1 is a plan view, partly in section, of a casing elevator embodying my invention; Fig. 2 is a reduced view, partly in side elevation and partly in vertical section, of the casing elevator shown in Fig. 1; Fig. 3 is an end view, in elevation, partly broken away, of the casing elevator shown in Figs. 1 and 2; Fig. 4

is a detail sectional view of a portion of the casing elevator, shown in Figs. 1 and 2, the lock mechanism being shown in elevation, and Fig. 5 is a plan view of the threaded bushing for the bolt chamber.

Like symbols refer to like parts wherever they occur.

In the drawings, A, B indicate the members of the elevator, C the bail thereof, and D the locking bolt which secures the members A and B in operative relation.

The bail-member A, which is of general U-shape, or somewhat more than a semi-circle to leave an opening for the introduction of the casing or tubing, is provided at diametrically opposite points on its exterior with trunnions 1, 1' for the reception of the journal eyes 1^a on the ends of the bail C whereby the bail is journaled on the body of the elevator. This bail member A has also on one of its arms a projecting perforated portion 2 for the reception of a pintle or pivot bolt 3 whereby the movable member B is hinged to or pivoted on the bail member A, and in its opposite arm a recess 4 for the reception of an interlocking portion of the member B. At the bottom of the recess 4 of member A is a further recess 5 which constitutes a keeper for the spring-actuated locking bolt carried by the movable member B.

The movable member B which is of general arc shape is of a size to close the opening in the bail member A to which it is hinged, and when closed on the member A to constitute therewith a complete circle or ring the internal diameter of which substantially corresponds with the external diameter of the casing or tubing which the elevator is intended to handle. This movable member B has at one side the perforated lugs or knuckle members 2^a for the reception of the pintle or pivot bolt 3, and on its opposite side a projection 6 which houses the automatic locking devices, and which is in a form adapted to enter the recess 4 of bail member A, so that by reason of the interlocking parts 2, 2^a and 6, 4 the hinged member B is solidly supported on and from the bail member A of the elevator. The portion 6 of the movable member B which houses the locking mechanism is bored through tangentially as at 7, to form a bolt chamber for the locking bolt of the elevator, which bolt chamber opens inwardly on the edge of projection 6 of the movable member B where it engages the bail

member A and also outwardly on the exterior surface of member B so that the bolt chamber 7 may be readily cleaned out when necessary. The bolt chamber 7 is in turn counterbored to form a shoulder 8 or seat for one end of a spring 10 which actuates the locking bolt D and is enlarged and threaded as at 9 for the reception of a threaded bushing 11 which confines the locking bolt D and its actuating spring.

D indicates the locking bolt which is preferably cylindrical at d where it is encircled by the coiled spring 10, is provided with an annular collar d' to form a seat for one end 15 of coiled spring 10, but is polygonal, preferably rectangular in cross section at d'' where it passes through the threaded bushing 11 by which it is confined, and is beveled as at d'' where the locking bolt engages and 20 is forced back by the member A, when the movable member B is swung into position to close bail member A. The bolt D has also a recess d'' in the collar d' for the reception of a pivoted latch whereby the bolt D may be 25 retracted when it is desired to open the movable member B to remove the elevator from the casing or tubing.

11 indicates a threaded bushing by means of which the locking bolt D and its actuating spring 10 are confined in the bolt chamber 7. The opening in said bushing 11 through which the end d'' of bolt D passes is polygonal, preferably rectangular, so that by the use of a wrench applied to part d'' of 35 bolt D the bolt and the bushing 11 can both be rotated to introduce or remove the bushing and bolt. This construction facilitates the removal of the locking bolt and bolt mechanism when it is desired to clean the 40 parts to insure certainty in their operation, or should it become necessary to remove the bolt and spring for purposes of repair.

12 indicates a latch member, having the 45 form of a bent lever, pivoted on the portion 6 of movable member B which portion of member B has been recessed as, at E to receive said latch member when the member B is in closed position on member A.

50 The short arm of the latch 12—or its equivalent the finger 12^a—engages in the notch or recess d'' of bolt D so that when the long arm of the latch member is pulled away from member B the bolt D will be retracted and its portion d'' , d'' will escape from keeper or recess 5 and thus release member B. A continued pull on latch member 12 will cause member B to swing open so that the elevator can be readily removed 60 from the casing.

It will be noted that a portion of the latch member 12 adjacent to its pivot 12^b projects slightly beyond the member B, and when the member B is closed and locked said portion of the latch 12 is opposite an eye or

journal 1^a of bail C. In order therefore to effectively secure the locking member against accidental movement or release when the member B is closed, or in operative position, a lug or cam projection 13 (see Fig. 2) 70 is located on bail C in such position as to stand in front of latch 12 when the bail C is vertical or the elevator is carrying its load but to move therefrom when the load on the elevator is removed and the bail C is at liberty to swing to one side, as indicated in dotted lines Fig. 3. In order to prevent the springing of bail C at any time, and a possible disengagement of the bail eyes from trunnions 1 of the bail member A, when the 80 elevator is loaded, annular disks 14 of greater diameter than the bail eyes are secured to the ends of trunnions 1, 1 by suitable set screws 15.

The construction being substantially such 85 as hereinbefore pointed out, the operation of the devices will be as follows: As the elevator is drawn up into the derrick for attachment to the casing or tubing the members A, B being open, will, as they leave the 90 floor of the derrick be swung toward the casing, which may be anywhere from three to six feet away from the center line of the derrick. The operator in the derrick will, when the elevator arrives opposite to him, 95 place one hand behind the bail member A and guide it on to the casing and with the other hand force to the hinged movable member B which will be automatically locked in its proper relation to member A. 100 In operation, as soon as strain is exerted on the elevator by the weight of the casing the bail will align itself with the casing, and in so doing the lug 13 on the journal eye 1^a of the bail will move in front of latch 12 and 105 secure the same against any accidental movement which would release the movable member B.

It will be noted that the height of the collar on the casing above the floor of the derrick need be but little more than the height of the members A, B of the elevator in order to permit the ready application of the elevator to the casing, and it will also be noted that in order to release the member B and 110 open the elevator to remove it from the casing the distance of the casing collar above the members A, B of the elevator need be only sufficient to take the weight of the casing off the members A, B and permit a slight 115 side movement of the bail C.

Having thus described my invention, what I claim and desire to secure by Letters Patent is:

1. In a casing elevator, the combination of 125 a bail, a bail member on which the bail is journaled, a movable member pivoted on the bail member, a lock for the movable member, said lock having locking engagement with the bail member, and means on 130

the bail for preventing the accidental movement of the lock when the elevator is loaded.

2. In a casing elevator, the combination of a bail, a bail member on which the bail is journaled, a movable member pivoted on the bail member, an automatic lock for the movable member, said lock being actuated independently of the bail, and means on the bail for preventing the accidental movement of the lock when the elevator is loaded.

3. In a casing elevator, the combination of a bail, a bail member on which the bail is journaled, a movable member pivoted on the bail member, a lock for the movable member, a latch for actuating the lock, and means on the bail for preventing the accidental movement of the latch when the elevator is loaded.

4. In a casing elevator, the combination of a bail, a bail member on which the bail is

journaled, a movable member pivoted on the bail member, a spring closed lock for the movable member, and means on the bail for preventing the accidental movement of the lock when the elevator is loaded. 25

5. In a casing elevator, the combination of a bail, a bail member on which the bail is journaled, a movable member pivoted on the bail member, a spring-actuated lock for the movable member, a latch for retracting the spring-actuated lock, and means on the bail for preventing the accidental movement of the latch when the elevator is loaded. 30

In testimony whereof I affix my signature, in the presence of two subscribing witnesses. 35
